INVENTOR

UNITED STATES PATENT OFFICE.

GEORGE R. AINSWORTH, OF GREAT NECK, NEW YORK.

DESIGN FOR AN ELECTRIC-LIGHTING FIXTURE.

60,716.

Specification for Design.

Patented Mar. 28, 1922.

Application filed May 16, 1921. Serial No. 470,024. Term of patent 14 years.

To all whom it may concern:

Be it known that I, GEORGE R. AINSWORTH, a citizen of the United States, residing at Great Neck, in the county of Nassau and State of New York, have invented a new, original, and ornamental Design for an Electric-Lighting Fixture, of which the following is a specification, reference being had to the accompanying drawing, forming part thereof.

The design comprised in the invention consists of a moulded glass globe with comparatively flat upper surface ornamented with a flattened ogee curve and a lower surface ornamented with a flattened ogee curve and with a circular raised portion in its center. The side of the globe is comparatively vertical and ornamented with a cavet-

to or the curve of a Greek cymatium and a pronounced tænia. The suspension of the fixture consists of an ornamental canopy at the ceiling, a chain and an ornamental holder for the globe. The bottom of the fixture is furnished with an ornamental tassel and rosette which may or may not be used according to the taste of the user. The complete lighting fixture, known as the Archer model, is shown in the accompanying drawing.

What I claim is:

The ornamental design for an electric lighting fixture as shown.

In testimony whereof, I have signed the foregoing specification.

GEORGE R. AINSWORTH.
